UNITED STATES PATENT OFFICE.

ARTHUR Q. WALSH, OF NEW YORK, N. Y.

DESIGN FOR A CIGAR OR CIGARETTE HOLDER.

40,677.

Specification for Design.

Patented May 3, 1910.

Application filed March 4, 1910. Serial No. 547,374. Term of patent 7 years.

To all whom it may concern:

Be it known that I, ARTHUR Q. WALSH, a subject of the King of Great Britain, and a resident of the city of New York, borough of Manhattan, in the county and State of New York, have invented a new, original, and ornamental Design for a Cigar or Cigarette Holder, of which the following is a specification, reference being had to the accompanying drawing, forming a part thereof.

Figure 1 is a perspective view of a cigar or cigarette holder, illustrating my new design; and Fig. 2 is a similar view of the same after the holder has been revolved 90°.

I claim:

The ornamental design for a cigar or cigarette holder, as shown.

ARTHUR Q. WALSH.
